UNITED STATES PATENT OFFICE

JOSEPH KIEREN, OF GILBERT, MINNESOTA

SWITCH STAND

Application filed June 16, 1930. Serial No. 461,606.

This invention appertains to railway switch mechanism and more particularly to a signal and lock means associated with the switch stand, whereby to indicate beyond peradventure of doubt when the switch is locked or unlocked.

The invention provides a signal, preferably electric, which is brought into action when the switch is unlocked and remains active until the switch is locked, said signal being by preference visual, and positioned for unobstructed observation by the engineer or operator of an approaching train.

The invention contemplates a signal included in an electric circuit which is controlled by a key to a lock mechanism associated with the switch throwing member to secure it when the switch is properly thrown.

While the drawings illustrate a preferred embodiment of the invention it is to be understood that in adapting the means to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a perspective of a switch stand embodying the invention.

Figure 2 is an enlarged fragmentary sectional view.

Figure 3 is a detail sectional view on the line 3—3 of Figure 2.

Figure 4 is a side view of a switch lock and coacting signal, showing the lock bolt projected into locking engagement and the signal circuit broken.

Figure 5 is a view similar to Figure 4, showing the lock bolt retracted and the signal circuit closed.

Figure 6 is a transverse sectional view on the line 6—6 of Figure 4.

Figure 7 is a perspective view of a modified form of lock casing, the cover plate and lock mechanism being removed.

Figure 8 is a side view of the modified form of lock and signal, the cover plate be-

ing omitted, showing the relation of the parts when the bolt is projected.

Figure 9 is a view similar to Figure 8 showing the position of the parts when the bolt is withdrawn.

55

Figure 10 is a transverse sectional view on the line 10—10 of Figure 8, looking to the left as indicated by the arrows.

Corresponding and like parts are referred to in the following description and designated in the several views of the drawings by like reference characters.

The numeral 1 designates a conventional form of switch stand of the open type and 2 the mast mounted therein and provided with 65 a crank arm 3 which is connected by means of bar 4 with the switch to be operated. These parts may be of any approved construction and are illustrated to demonstrate the application of the invention. A collar 5 70 or like part is secured to the mast 2 and the switch throwing lever 6 is pivoted thereto and adapted to engage notches 7 in the top of the switch stand to hold the switch in the desired position. A lock mechanism is attached to the collar 5 and serves to secure the switch throwing member 6 against movement when the switch is thrown and the part engaged with one or the other of the notches 7.

The lock mechanism may be of any determinate construction and includes a casing 8 in which the lock mechanism is housed. The casing 8 may be secured to the collar 5 in any substantial manner. The lock mechanism in-

cludes a bolt 9 and tumbler 10 which are 85 adapted to be actuated by means of a key 11. A stop 12 limits the rotation of the key when the bolt 9 is fully retracted, as indicated most clearly in Figure 5 of the drawings. This precludes withdrawal of the key from the 90 lock until returned to normal position for insertion or withdrawal from the lock. When the lever 6 engages either one of the notches 7 an opening in the pivotal end thereof is positioned opposite and in line with the bolt 9 which, when projected, enters said opening and locks the lever 6, as indicated most clearly in Figure 3 of the drawings. It is necessary to retract the bolt 9 to release the lever 6 before the latter can be moved to throw the 95 100

switch and when the switch is thrown the lever 6 occupies a position opposite one or the other of the notches 7 and may be swung downwardly into engagement therewith and locked by projecting the bolt 9 as herein described.

A signal mechanism is associated with the switch stand and is controlled by the lock mechanism, said signal being active when the switch is unlocked and inactive when the switch is properly thrown and locked. This signal is electrically actuated and is visual and contemplates a red light which is prominently displayed to be readily observed by the engineer or operator of an approaching train. The signal includes a lantern 13 or casing provided in its sides with openings in which are fitted lenses or plates. A lamp bulb 14 is disposed within the lantern or casing 13 and is included in an electric circuit. The signal emits red rays symbolical of danger. The current may be derived from a suitable source, according to conditions. If convenient, the current may be obtained from a service line and in the absence thereof, a battery 15 may be utilized. A case 16 houses the battery 15 and is attached to the mast 2, one pole of the battery being grounded to the mast and a conductor 17 leading from the other pole and connecting with a strip 18 mounted upon the lock bolt 9 and electrically insulated therefrom. A contact 19 is connected with or forms a part of the conducting means 18. A spring contact 20 is connected to the casing 8 and is connected by a conductor 21 to a spring contact 22 likewise connected to the casing 8 and engaging a terminal of the lamp filament, the other terminal of the lamp filament being grounded to the casing 8. While the contacts 20 and 22 are connected to the casing 8, they are electrically insulated therefrom. When the bolt 9 is projected into locking engagement with the switch throwing member 6, the signal circuit is broken, as indicated most clearly in Figure 4 of the drawings. When the bolt 9 is retracted or withdrawn from locking engagement with the switch throwing member 6, the signal circuit is closed, as indicated most clearly in Figure 5 of the drawings, thereby indicating that the switch is not locked, even though it may be properly thrown. It is observed that the key may not be withdrawn from the lock when the bolt 9 is retracted and for the trainman to obtain the key, it is necessary to project the bolt 9. Should the switch not be properly thrown and locked, the blame may be readily fixed. Should the switch be properly thrown but not locked, the signal light will be displayed, thereby serving as a warning to the approaching train that the switch is not locked.

In the modified form of lock, a block 23 is provided and is mounted in guides 24 and

in one position, engages a shoulder 25 of the bolt 9 and holds the latter in retracted position. The block 23 is urged laterally by means of a spring 26 and is formed with a projection 27 adapted to operate in an opening 70 formed in the cover plate 29. When the bolt 9 is withdrawn by use of the key 11, it is held retracted by the block 23 engaging the stop shoulder 25. The key 11 may be withdrawn from the lock and when it is required to project the bolt into operative position, the block 23 is pressed inwardly and clears the stop shoulder 25, thereby permitting the bolt to be projected by means of a spring 30 which is interposed between the rear end of the bolt 9 and the rear wall of the casing 8. This form of lock is interchangeable with that shown most clearly in Figure 4 of the drawings.

As shown most clearly in Figure 7 of the drawings, the lock casing is of integral construction, thereby obviating the formation of joints and the use of fastening means. The stop pin 12, key pin 31, guide pin 32, and guides 24, form a part of the lock casing as 80 well as the face plate, the back plate, and enclosing walls. The pin 32 operates in a longitudinal slot 34 formed in the body of the bolt 9.

What is claimed is:

1. The combination with a switch stand and a switch throwing member, of a lock mechanism including a lock bolt for securing the switch throwing member to lock the switch in adjusted position, and a signal controlled by the lock bolt and active when the lock bolt is projected to lock the switch throwing member and inactive when the lock bolt is retracted to release the switch throwing member. 100
2. The combination with a switch stand and a switch throwing member, of a lock mechanism including a bolt adapted to be projected into locking engagement with the switch throwing member to lock the switch, and a signal light included in a circuit which is adapted to be closed when the lock bolt is projected and broken when the lock bolt is retracted. 110
3. The combination with a switch stand and a switch throwing member, of a lock mechanism including a bolt adapted to be projected into locking engagement with the switch throwing member to lock the switch, and a signal light included in a circuit having a part mounted upon the lock bolt and movable therewith to close the circuit when the bolt is withdrawn and to close the circuit when the bolt is projected into locking engagement with the switch throwing member to lock the switch in adjusted position. 120

In testimony whereof I affix my signature.
JOSEPH KIEREN. [L.S.]
